DESIGN FOR MACARONI OR SIMILAR ARTICLE

Gennaro Cirillo, Brooklyn, N. Y.

Substituted for abandoned application Serial No.
D. 58,150, August 16, 1935. This application
November 6, 1936, Serial No. D. 65,746

Term of patent 3½ years

To all whom it may concern:

Be it known that I, Gennaro Cirillo, a citizen of the United States and a resident of Brooklyn, in the county of Kings and State of New York, have invented and produced a new, original, and ornamental Design for Macaroni or Similar Article, of which the following is a specification, reference being had to the accompanying drawing, forming part thereof:—

This case is a substitute for applicant's prior application filed Aug. 16, 1935, Serial No. D. 58,150.

Fig. 1 is an end view on an enlarged scale of a macaroni or similar article showing my new design; and

Fig. 2 is a view thereof in side elevation.

I claim:

The ornamental design for macaroni or similar article as shown.

GENNARO CIRILLO.
